(57) **CLAIM**

I claim the ornamental design for a wireless speaker, as shown and described.

DESCRIPTION

FIG. 1 is a front perspective view of a wireless speaker, showing my new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines shown represent unclaimed subject matter and form no part of the claimed design.
